United States Patent Office

Des. 232,611
Patented Sept. 3, 1974

232,611

CABINET DOOR

Warren A. Dillen, Louisville, Ky., assignor to
H. J. Scheirich Company

Filed Sept. 6, 1972, Ser. No. 286,664

Term of patent 14 years

Int. Cl. D6—06

U.S. Cl. D6—192

FIG. 1 is a front elevational view of a cabinet door showing my new design; and

FIG. 2 is a sectional view along line 2—2 of FIG. 1.
I claim:

The ornamental design for a cabinet door, substantially as shown and described.
